UNITED STATES PATENT OFFICE

PERCIVAL W. JONES, OF WARWICK, RHODE ISLAND, ASSIGNOR TO ROSENHEIM CO. INC., OF PROVIDENCE, RHODE ISLAND, A CORPORATION OF RHODE ISLAND

EXTENSION DEVICE

Application filed December 10, 1928. Serial No. 324,883.

This invention relates to an extension device for a wrist strap and has for its object to provide a construction by which the extension is obtained by bodily moving the parts away from each other in the direction of the longitudinal extent of the strap rather than by unfolding sections which are hingedly attached together and lie one over the other.

10 A further object of the invention is the connecting of two separable members together by means of lazy-tongs to permit the separation of the members one from the other and the enlargement of the strap to which they are connected with one of the members so formed as to house the lazy-tongs when in folded position.

15 This invention further consists in a construction for locking the members in contracted position and the provision of means for releasably securing one end of the strap to one of the members.

20 With these and other objects in view, the invention consists of certain novel features of construction, as will be more fully described, and particularly pointed out in the appended claims.

25 In the accompanying drawings:

Figure 1 is a top plan view of the extension device in contracted position.

Figure 2 is a top plan view with parts broken away showing the device in partly extended position.

25 Figure 3 is a top plan view with parts broken away and in section showing the arrangement of the lazy-tongs in folded position.

Figure 4 is a side elevation of the device in contracted position.

30 Figure 5 is a perspective view of one part of the housing member.

Figure 6 is a perspective view of another part of the housing member.

Figure 7 is a perspective view of the housing member of the extension device assembled with the clamp in released position and the catch in unlocked position.

35 Figure 8 is a sectional view showing the clamp in position to attach the strap to the housing member.

Figure 9 is a sectional view on line 9—9 of Figure 10.

Figure 10 is a sectional view on substantially line 10—10 of Figure 9.

In extension devices of the type used for 55 enlarging the encircling size of a wrist band or the like, it is found desirable to provide a construction which is extremely thin and neat on the arm of the wearer and one which may permit of an enlarging movement by a 60 separation of its parts bodily in the direction of longitudinal extent of the strap rather than an unfolding of hingedly connected sections as is common in the art, and in order to provide a construction to obtain these desirable results, I have formed a housing with 65 lazy tongs mounted in the housing which may extend therefrom to enlarge the size of the wrist strap for removal over the hand of 70 the wearer and have provided a suitable lock for preventing such extension when the device is in working or operating position, and 75 I have also provided in such construction a means for detachably securing one end of a strap to this device, and the following is a detailed description of the present embodiment of this invention showing the preferred means by which these advantageous results may be accomplished:

With reference to the drawings, 10 designates the channel-shaped body of the housing member having a top wall 11 and side walls 12 which receive between them the bottom wall 13 having side flanges 14 to form a 80 housing space 15 between the top and bottom walls. The flanges 14 are of a dimension to space the bottom wall 13 from the top wall 11 a distance less than the width of the side walls 12 so that the side walls will extend 85 beyond the bottom wall 13 a distance to accommodate and conceal the free end of the clamp as will be presently described. Notches 16 are provided at the juncture of the bottom wall 13 and its flanges 14 to receive fingers 17 extending from the side walls and into their notches to hold the bottom wall 90 in place.

The bottom wall 13 is a length less than the channel body 10 to leave the top and side 100

walls protruding beyond the bottom at end 18. In this portion of the side walls, openings 19 are provided to pivotally receive the gripper or clamp 20 having a lever arm 21 notched as at 22 to receive the fingers 17 and lie flush against the bottom wall 13 between the portions of the side walls 12 which extend therebeyond whereby the bottom surface presented by all parts of the device are in the same plane and the clamp is concealed.

The cam acting strap engaging portion 23 of this pivotally mounted clamp is adapted to swing and force the strap against the top wall 11 to securely attach it to the housing member. In the illustration shown the strap consists of a plurality of block links 24 hingedly connected together as illustrated in Figure 8. The cam acting portion 23 is designed to extend into one of the spaces between the links 24 to firmly hold the end of the strap to the extension device. An adjustment as to size can be readily accomplished in this manner by cutting off the strap to the desired length before clamping it to the housing section.

In the housing space 15 one end of a series of jointed bars 27 and 28 pivoted together at their ends and points of crossing in a lazy tong arrangement is secured by suitable means 26 such as a rivet or the like, as illustrated in Figures 2 and 3. At the other end of this lazy tongs, the member 29 of the extension device is secured, which in turn is secured to the end link of an end of the strap. When it is desired that the device be extended, the member 29 is moved away from the housing member and an extension of the lazy tongs takes place, as illustrated in Figure 2, as whereas when the device is moved to contracted position, the lazy tongs are folded into the position illustrated in Figure 3 with the end member 29 positioned in the notches 30 formed in the side walls 12 of the housing member.

This end member 29 is locked in contracted position in the notches 30 by means of a yoke 31 having side arms 32 pivoted as at 33 to the side walls 12 of the housing member. The arms are joined together to support each other and move in unison as at 34 and are notched as at 35 with an undercut portion 36 so as to prevent accidental raising of the yoke to release the member 29, it being understood that the longitudinal strain on the strap pulls the member 29 into these undercut portions and that in order that the same be released, a slight movement in a direction to contract the lazy tongs will be necessary to move the member 29 from the undercut portion of the notch to permit an upward swinging of the yoke for release of the member 29 and expansion or enlargement of the strap.

A construction of this character may be made exceedingly thin to take up the mini-

mum amount of space on the arm of the wearer and to afford a neat appearance when worn.

The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. An extension device for a wrist strap or the like comprising a housing member attached to one end of the strap, extendible lazy tongs having one end secured in said housing and foldable therein, a member secured to the other end of said lazy tongs and attached to the other end of the strap and means for securing said members together and said lazy tongs in folded position in said housing.

2. An extension device for a wrist strap or the like comprising a housing member attached to one end of the strap, extendible lazy tongs having one end secured in said housing and foldable therein, a member secured to the other end of said lazy tongs and attached to the other end of the strap and a yoke pivoted to the said housing member and swingable over the other member to secure the members together and said lazy tongs in folded position.

3. An extension device for a wrist strap or the like comprising a channel shape member having a top wall and side walls, a clamp pivoted between the side wall of the member to receive and clamp between it and the top wall one end of a strap, a bottom wall spaced from the top wall to provide a housing space and positioned inwardly from the edge of the side wall a distance substantially the thickness of the free end of the clamp, lazy tongs secured in the housing space and extendible therefrom, a member secured to the end of said lazy tongs and attached to the other end of the strap.

4. An extension device for a wrist strap or the like comprising a channel shape member having a top wall and side walls, means for securing one end of the strap thereto, a bottom wall spaced from the top wall to provide a housing space, lazy tongs secured in the housing space and extendible therefrom, a member secured to the end of said lazy tongs and attached to the other end of the strap, said side walls being notched on their ends to receive said member, and means to secure said members in contracted position.

5. An extension device for a wrist strap or the like comprising a channel shape member having a top wall and side walls, means for securing one end of the strap thereto, a bottom wall spaced from the top wall to provide a housing space, lazy tongs secured in the housing space and extendible therefrom, a member secured to the end of said lazy tongs and at-

- tached to the other end of the strap, a yoke pivoted to said side walls having undercut notches to swing over and receive said member to lock it against extension.
- 5 6. An extension device for a wrist strap or the like comprising a channel shape member having a top wall and side walls, a clamp pivoted between the side wall of the member to receive and clamp between it and the top 10 wall one end of a strap, a bottom wall spaced from the top wall to provide a housing space and positioned inwardly from the edge of the side wall a distance substantially the thickness of the free end of the clamp, lazy tongs 15 secured in the housing space and extendible therefrom, a member secured to the end of said lazy tongs and attached to the other end of the strap, said side walls being notched on their ends to receive said member, a yoke 20 pivoted to said side walls having undercut notches to swing over and receive said member to lock it against extension.
7. An extension device for a wrist strap or the like comprising two members located in 25 substantially the same plane, each adapted to be connected to an end of a strap, extensible means connecting said members together, said means comprising relatively movable parts arranged to direct a continuous relative movement of said members in substantially the 30 plane in which they are located and means for releasably locking said members in adjacency.
8. An extension device for a wrist strap or the like comprising two members located in 35 substantially the same plane, each adapted to be connected to an end of a strap, inelastic extensible means connecting said members together, said means comprising relatively 40 movable parts arranged to direct a continuous relative movement of said members in substantially the plane in which they are located and means for releasably locking said members in adjacency.
- 45 9. An extension device for a wrist strap or the like comprising two members located in substantially the same plane, each adapted to be connected to an end of a strap, extensible means connecting said members together, said 50 means comprising relatively movable parts arranged to direct a continuous relative movement of said members in substantially the plane in which they are located and means for releasably locking said members in adjacency, one of said members housing said extensible means when the members are in adjacency.
- 55 10. In combination with a non-extendible 60 wrist watch strap, an extension device comprising two members each connected to an end of the strap, extensible means connecting said members including a series of similar elements arranged to carry one of said members toward or from the other by a continu-

ous uniform relative movement of said elements and means for releasably locking said members in adjacency.

In testimony whereof I affix my signature.
